(57) **CLAIM**

The ornamental design for a lower rear bumper for a vehicle, as shown and described.

DESCRIPTION

FIG. 1 is a right front perspective view of a lower rear bumper for a vehicle according to the present invention.

FIG. 2 is a left front perspective view of the lower rear bumper shown in FIG. 1.

FIG. 3 is a right rear perspective view thereof.

FIG. 4 is a left rear perspective view thereof.

FIG. 5 is a front view thereof.

FIG. 6 is a rear view thereof.

FIG. 7 is a right side view thereof.

FIG. 8 is a left side view thereof.

FIG. 9 is a top view thereof.

FIG. 10 is a bottom view thereof; and,

FIG. 11 is a right front perspective view of the lower rear bumper shown in FIGS. 1-10, mounted on a vehicle, with the rest of the vehicle shown in de-emphasized and half-tone portions so as to illustrate environmental structure. These portions form no part of the claimed invention. More particularly, in FIG. 11, the inventive lower rear bumper is shown within the broken line, and the elements shown outside of the broken line form no part of the claimed invention, but are instead included to show environmental aspects thereof.
